RADIO BOMB RELEASE SYSTEM

Daniel Blitz, Newtonville, Mass., assignor to Radio Corporation of America, a corporation of Delaware

Application October 18, 1946, Serial No. 704,244

4 Claims. (Cl. 343—7)

1

This invention relates to radio bomb release systems, and more particularly to improvements in systems of the type which transmit a signal from the bombing craft to a selected target, receive the signal after reflection by the target, and compare the transmitted and received signals to determine the instant at which a bomb should be released to hit the target. One such system, using frequency modulated signals, is described in copending U. S. patent application Serial No. 524,794, filed March 2, 1944, by Royden C. Sanders, Jr., and William R. Mercer, now Patent No. 2,412,632, issued December 17, 1946, and entitled Radio bomb release system.

Owing to occasional transmission over multiple paths, caused by reflection from the sea or terrain lying between the bomber and its target, the signal received at the bombing craft will fade, disappearing and returning at intervals as the target is approached. When the signal disappears, the effect is similar to that of a remote target, and the computer circuit tends to adjust itself accordingly. Upon reappearance of the signal, a certain amount of time is required for the computer to readjust to the true conditions. If this occurs just prior to the proper instant of release, no bomb will be dropped until the signal reappears, and the computer reaches its proper value, which may be long after the proper instant of release. If the fade is sufficiently long so that the target is passed before the signal returns, no bomb will be dropped, although the bomber may fly directly over the target.

The principal object of the present invention is to provide, in a system of the described type, means for preventing such delay or failure to release, by extrapolation, during fading, of the latest available information.

Another object is to achieve the foregoing with a minimum of additional circuits and components, avoiding any substantial increase in weight and complication of the equipment.

The invention will be described with reference to the accompanying drawing, wherein:

Figure 1 is a schematic diagram of a bomb release system embodying the present invention.

Figure 2 is a graph showing the variations in frequency of the signals transmitted and received in the operation of the system of Figure 1,

2

Figure 3 is a graph showing the variations in frequency of a beat signal produced in the operation of the system of Figure 1.

Figure 4 is a graph showing typical variation, as a target is approached, of a control voltage produced in the operation of the system of Figure 1, and

Figure 5 is a graph illustrating ideal variations of said control voltage at high and low speeds of the bomber craft, and a compromise between said extremes.

Refer to Figure 1, which illustrates a system like that disclosed in the aforementioned copending Sanders application. A radio transmitter 1, provided with an antenna 3, is connected to a frequency modulator 5. The modulator 5 may be of the vibratory variable capacitor type described in patent application Serial No. 471,003, filed January 1, 1943, by Sydney V. Perry and entitled Capacity modulator unit. A square wave generator 7 excites the modulator 5 through a wave shaping circuit 9, which integrates the square wave to produce substantially symmetrical triangular wave variation in the frequency of the transmitter 1.

A receiving antenna 11 is coupled to a detector 13. The transmitter 1 is also coupled to the detector 13 through a transmission line 15. The output of the detector 13 is applied to an amplifier 17, and thence through an amplitude limiter 19 to a differential counter circuit 21. The counter circuit 21 is of the type described in said Sanders application Serial No. 524,794, now Patent No. 2,412,632, issued December 17, 1946, comprising two averaging cycle counters provided with a common load resistor 23, arranged so that one provides a current flowing upward in the resistor 23 and the other provides a current flowing downward in the resistor 23. The counter 21 is electronically switched by square wave voltage from the generator 7, so that current flows down in the resistor 23 when the frequency of the transmitter 1 is increasing, and up when the transmitted frequency is decreasing.

The counter output circuit is biased to a voltage E_A by means of a voltage divider 25 connected across a D.-C. source with its adjustable tap connected to the lower end of the load resistor 23.

A relay circuit 27 is connected to energize a bomb release mechanism, not shown. An arming

switch 28 is included between the relay 27 and the release mechanism. The relay circuit 27 is designed to actuate the release when the voltage of its input decreases to a predetermined value. One such relay circuit, using a cathode-input amplifier, is described in the above-mentioned Sanders application.

In the system of said Sanders application, the counter output is applied directly to the relay circuit. The present system differs therefrom in that a so-called "memory" circuit is provided between the counter and the relay. A capacitor 29 is connected across the input terminals of the relay 27. The upper terminal of the capacitor 29, together with the corresponding input terminal of the relay, is connected through a diode 31 to the counter load resistor 23. The diode 31 is arranged to allow conduction only from the capacitor 29 to the resistor 23. A low pass filter comprising a resistor 33 and a capacitor 35 may be included between the resistor 23 and the diode 31.

A resistor 37 is connected at one end to the upper terminal of the capacitor 29. The other end of the resistor 37 goes to two switches, 39 and 41. The switch 39, when closed, connects the resistor 39 to the tap on the voltage divider 25. The switch 41, when closed, connects the resistor 39 to the positive end of the divider 25, which is at a potential in excess of that at which the relay 27 operates.

The switch 41 is ganged with the arming switch 28 so that when the switch 28 is open, the switch 41 is closed, and vice versa. The switch 39 is arranged to be held open normally by an electromagnet 43, and to close when the magnet 43 is deenergized. The coil of the magnet 43 is connected to the output of a rectifier 45, which is supplied from the output of the amplifier 17.

The operation of the described system is as follows:

The transmitter 1 provides a frequency modulated signal which is radiated by the antenna 3. Some of the radiated energy strikes the target and is reflected back to the antenna 11 and applied to the detector 13, where it is mixed with transmitter output reaching the detector through the line 15.

Referring to Figure 2, the frequency of the transmitter output varies as shown by the solid line 201. The frequency of the signal received at the antenna 11 varies as shown by the dash line 203. The variations in the received signal are delayed with respect to those of the transmitted signal by a time T_d , which is the period required for radiation to travel from the antenna 3 to the target and back to the antenna 11, and hence is proportional to the distance, d . In addition (assuming the bomber is going toward the target) the frequency of the received signal is shifted upward owing to doppler effect. This upward shift f_s is proportional to the speed of approach s of the bomber to the target.

The output of the detector 13 includes a beat signal whose frequency f_b is the difference in frequency of the transmitter output and the received signal. The beat frequency f_b is lower during upsweep, or increase of transmitter frequency, than it is during downsweep, or decrease of transmitter frequency. The difference between the upper and lower values of f_b is proportional to the speed s . The average value of f_b is proportional to the distance d .

The beat output of the detector 13 is amplified by the amplifier 17, then limited to a constant

amplitude by the limiter 19 and applied to the differential counter 21. The counter 21 provides, during upsweep, a current i_u in the resistor 23, proportional to the lower value of the beat frequency f_b . During downsweep, the counter 21 produces a current i_d in the opposite direction to the current i_u and proportional to the upper value of the beat frequency f_b .

$$i_u = k_1 (ad - bv)$$

and

$$i_d = -k_2 (ad + bv)$$

where a and b are constants determined in the design of the system, and k_1 and k_2 are the sensitivities of the counter circuit when operating positive and negative respectively. The average current in the resistor 23 (flowing downward) is

$$i_a = (k_1 - k_2) ad - (k_1 + k_2) bv$$

and the resulting voltage drop (positive at the upper end of the resistor 23) is

$$E_1 = Ad - Bv$$

where

$$A = R(k_1 - k_2) a$$

and

$$B = R(k_1 + k_2) b$$

The total potential at the upper end of the resistor 23, referred to ground, is

$$E_c = E_1 + E_A$$

As the bomber approaches the target, E_c decreases because d is decreasing. The bias voltage E_1 and the constants a , b , k_1 and k_2 are determined with respect to each other in advance, making due allowance for the altitude H at which the bombing run is to be made, so that E_c becomes equal to the voltage E_D at which the relay is set to operate when

$$\frac{d}{v} = \sqrt{\frac{2H}{g}}$$

where g is the acceleration of gravity, 32.2 feet per second per second.

The quantity

$$\frac{d}{v}$$

is referred to hereinafter as the time from target, and is defined as the time which will be required under present conditions for the bomber to reach a point directly over the target. The quantity

$$\sqrt{\frac{2H}{g}}$$

is the time of fall, i. e. the time required for a bomb released at an altitude H to reach the ground. If release is effected when the time from target equals the time of fall, the bomb will strike the target.

Owing to the fact that the radio equipment measures the slant speed and slant distance rather than the horizontal components of speed and distance, the equipment must be adjusted so that E_1 follows an approximation rather than the true relation between speed and distance. This is described in detail in the above-mentioned Sanders application. It is sufficient for the purpose of the present description to note that E_c decreases with decreasing time from target, and becomes equal to E_D when the time from target is equal to the time of fall.

Now suppose that as the bomber approaches the target, the received signal fades out. The control voltage E_c , which has been decreasing in a substantially continuous manner (see Figure 4),

immediately starts up to a maximum value corresponding to that which appears normally when the target is remote. This results from thermal noise in the detector 11, which causes the counter 21 to operate at random during both upsweep and downsweep, making both i_u and i_d large, as they would be with a distant target and substantially no velocity of approach.

This condition persists until the signal comes back again, whereupon the counter output current i_d again bears the correct relationship to d and v . However, the control voltage E_c does not return immediately to the proper value, because the filter capacitor 24 must be discharged down to E_c . As illustrated in Figure 4, this may not occur until after the time from target has decreased to less than the time of fall, and in the above-described Sanders system release will take place too late, or not at all, depending upon whether or not E_c gets down to E_D before the bomber passes over the target and loses the signal entirely.

In the operation of the instant system, the switches 28 and 41 are initially in the positions shown in Figure 1. As soon as a usable target signal is picked up, the coil 43 is energized to open the switch 39. The capacitor 29 is then charged, through the switch 41 and the resistor 31, to the full voltage appearing across the voltage divider 25. As the bombing run is started, the arming switch 28 is closed, opening the switch 41. The capacitor 29 then discharges through the diode 31 and the resistor 23 until the voltage across it is equal to the voltage E_c .

As E_c decreases in the manner shown in Figure 4, the capacitor 29 continues to discharge through the diode 31 to equalize its voltage with E_c . When the received signal fades, and E_c increases, the diode 31 blocks, since it cannot conduct toward the capacitor 29. The switch 39 closes and the capacitor 29 continues to discharge through the resistor 37. The resistor 37 and the capacitor 29 are so proportioned that this discharge occurs at a rate approximating the normal decrease of E_c , which is indicated by the dash line 403 in Figure 4.

If the signal returns before the bomber reaches the release point, the magnet 43 reopens the switch 39 and the capacitor 29 starts to discharge through the diode as soon as E_c falls below the voltage then existing across the capacitor 29. Thus if E_c returns to its correct value before the time from target becomes equal to the time of fall, the relay is controlled by current information, since the voltage applied thereto is kept equal to E_c . If E_c does not return to its proper value in time, release takes place anyway as soon as the capacitor 29 has discharged sufficiently through the resistor 37.

Referring to Figure 5, the curve 501 represents the variation of E_c with time when the bomber is approaching the target at a relatively high speed, and the curve 503 shows how E_c varies when the bomber approaches at a relatively low speed. The resistor 37 and capacitor 29 are proportioned to provide a discharge rate approximately midway between these conditions, as shown by the dash line 505, thus permitting an approximately correct time of release, even if the signal has faded out at the time.

I claim as my invention:

1. A bomb release system including, on a mobile craft, means transmitting a signal to a selected target and means for receiving said signal after reflection by said target to provide a control volt-

age bearing a predetermined relationship to the time from target, relay means responsive to decrease of input voltage to a predetermined value to effect bomb release, a storage device connected across the input terminals of said relay means, means for initially charging said storage device to a predetermined terminal voltage in excess of that which effects release, means normally discharging said storage device to a terminal voltage equal to said control voltage, a further discharge path, and means responsive to failure of said received signal to connect said further discharge path across said storage device to discharge said storage device at a rate approximating the normal rate of decrease of said control voltage.

2. A bomb release system including, on a mobile craft, means transmitting a signal to a selected target and means for receiving said signal after reflection by said target to provide a control voltage bearing a predetermined relationship to the time from target, relay means responsive to decrease of input voltage to a predetermined value to effect bomb release, a capacitor connected across the input terminals of said relay means, means for initially charging said capacitor to a predetermined voltage in excess of that which effects release, a discharge path including a unilateral conductor connected to said capacitor and means to apply said control voltage to said discharge path to normally prevent discharge of said capacitor to a voltage less than said control voltage, a resistor, and means responsive to failure of said received signal to connect said resistor across said capacitor to discharge said capacitor at a rate approximating the normal rate of decrease of said control voltage.

3. In a bomb release system including on a mobile craft means transmitting a signal to a selected target, means for receiving said signal after reflection by said target, computer means responsive to said transmitted and received signals to provide a control voltage bearing a predetermined relationship to the time from target, and relay means responsive to decrease of input voltage to a predetermined value to effect bomb release, a system for compensating the effects of fading or failure of said received signal including a capacitor connected across the input terminals of said relay means, means for initially charging said capacitor to a predetermined voltage in excess of that which effects release, a unilateral conductor connected between said computer means and said capacitor to prevent conduction from said computer means to said capacitor, and provide a path for discharge of said capacitor to a voltage equal to said control voltage provided by said computer, a resistor, and means responsive to failure of said received signal to connect said resistor across said capacitor to discharge said capacitor at a rate approximating the normal rate of decrease of said control voltage.

4. In a bomb release system including on a mobile craft means transmitting a signal to a selected target, means for receiving said signal after reflection by said target, computer means responsive to said transmitted and received signals to provide a control voltage bearing a predetermined relationship to the time from target, and relay means responsive to decrease of input voltage to a predetermined value to effect bomb release, a system for compensating the effects of fading or failure of said received signal including a capacitor connected across the input terminals of said relay means, a direct current source of predetermined voltage in excess of that which

effects release, an arming device including means for initially connecting said capacitor to said source and, upon arming, to disconnect it from said source, a unilateral conductor connected between said computer means and said capacitor to prevent conduction from said computer means to said capacitor, and provide normally a path for discharge of said capacitor to a voltage equal to said control voltage provided by said computer, a resistor, and means responsive to failure of said received signal to connect said resistor across said capacitor to discharge said capacitor at a rate approximating the normal rate of decrease of said control voltage.
